Des. 178,905
Patented Oct. 2, 1956

178,905

EXPANSIBLE LINK CHAIN BRACELET OR SIMILAR ARTICLE

Jeanne Allen Sharp and Sherie Kent Spitz, Brooklyn,
N. Y., assignors to Flex-Let Corporation, East Providence,
R. I., a corporation of Rhode Island

Application February 9, 1955, Serial No. 34,426

Term of patent 7 years

(Cl. D45—4)

FIG. 1

FIG. 2

FIG. 3

FIG. 4

Figure 1 is a top plan view of an expansible link chain bracelet or similar article embodying our new design;

Figure 2 is a side elevational view of the link chain bracelet of Figure 1;

Figure 3 is a top plan view thereof in its expanded relationship; and

Figure 4 is an enlarged detail perspective view of one of the shells employed in our new design.

We claim:

The ornamental design for an expansible link chain bracelet or similar article, substantially as shown.
